(57) CLAIM

The ornamental design for the dashboard with screen as shown and described.

DESCRIPTION

FIG. 1 is a perspective view of the dashboard with screen according to my design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof.

The broken lines shown in the Figures depict portions of the dashboard with screen that form no part of the claimed design.
